UNITED STATES PATENT OFFICE

2,552,671

VEHICLE WINDOW REGULATOR

Burton S. Floraday, Toledo, Ohio, assignor to
Detroit Harvester Company, Detroit, Mich., a
corporation of Michigan

Application December 4, 1944, Serial No. 566,552

3 Claims. (Cl. 268—126)

1

This invention relates to window regulators but more particularly to regulators for use in connection with vehicle windows, and an object is to produce a simple and efficient regulator mechanism for imparting a straight up and down movement to a window glass, the lower edge portion of which slopes or inclines downwardly.

Another object is to adapt a cross arm window regulator mechanism for use with a window glass, the lower edge portion of which inclines downwardly from one side to the other and to achieve a substantially rectilinear movement in directions coincident with the up and down plane of the glass.

Other objects and advantages will hereinafter appear, and for purposes of illustration but not of limitation, an embodiment of the invention is shown on the accompanying drawings, in which

Figure 1 is an elevational view of an automobile door with parts broken away, illustrating a window regulating mechanism embodying the present invention;

Figure 2 is a sectional plan view through the door taken substantially along the line 2—2 of Figure 1; and

Figure 3 is a perspective view of an end portion of one of the regulator arms.

Generally, a vehicle door D to which the present invention may be applied, comprises a window opening 5 arranged above a hollow well section 6 enclosed by inner and outer door panels 7 and 8 respectively. The opening 5 while of generally rectangular shape, may have a sloping pillar post as indicated at 9, and a sloping sill 10 inclined at an angle to the horizontal, as a matter of design. A window or glass panel 11 for closing the opening 5 is generally correspondingly shaped. The well section 6 is provided for concealing the window operating mechanism 12, which is supported on the inner door panel 7 and further provides space into which the window panel 11 is lowered.

Window panels of the present type are generally adapted to slide vertically within the window opening and well in the conventional manner guided between vertically disposed channels 14. The guide channels are arranged slidably to engage the side edges of the window glass 11 as it is moved up or down by the regulating mechanism. As presently disclosed the window glass 11 conforms to substantially the shape of the window opening so that when it is lowered, the upper margin of the sloping edge is spaced away from the pillar of the door. The panel is partially supported against tilting or rocking by

2

means of a channel member 16, which is secured to the lower edge of the window panel and on the end adjacent the sloping edge of the panel, is equipped with a guide engaging member 17. The channel member 16 is further provided with a pair of spaced retainers 18, one of which has an elongate slot to receive a stud 19 carried by one of the regulator arms. The left hand retainer is pivoted by a stud 19' to an adjacent regulator arm. The retainers are disposed in a plane parallel with the lower edge of the window panel which plane, as previously mentioned, lies at an angle to a horizontal plane passing through the regulator support.

15 The regulator mechanism 12 is generally of conventional design and comprises a driving arm 20 mounted at its lower end for swinging movement about a pivot stud 21 carried by a mounting plate 22. The plate 22 is suitably secured in 20 the usual manner by screws to the inner door panel 7. A lower arm 23 fixed to the lower end of the arm 20 and forming a bell crank therewith, is connected by a link 24 to a gear sector 25 incorporated in a standard regulator operating mechanism 26 also secured to the inner door panel 7. A pinion 28 meshing with the gear sector 25 is mounted on a stub shaft 29 which projects outwardly from the door to receive a conventional crank handle (not shown) for manipulating the regulator. A balance cross arm 30 of substantially the length of the driving arm 20 is rotatably pivoted on the driving arm medially of its length on a pivot stud 31 and has its lower end slidably connected to the mounting plate 22. A spiral counterbalancing spring 31a is mounted in the usual manner on the pivot stud for the gear sector 25. The upper end of the arm 30 is pivotally connected by the stud 19' to the left hand retainer 18.

40 In order for the regulator arms 20 and 30 to transmit straight up and down motion to the window panel 11, the outer ends of the arms are required to swing through arcs of equal radii. This is not possible as is apparent in the drawings, if the arm 20 is of sufficient length to be connected directly by means of the stud 19 to the right hand retainer 18. By this arrangement, the window would be caused to rock and thus bind within the guide channels. In order to overcome 45 this difficulty, the stud 19 is offset to one side of the arm 20 on a radius struck from the pivot 21 and equal to the length of the arm 30 between its end connections. In order to support the stud 19 in this location, I provide a triangular extension plate 33, which is secured by rivets 34 to the

end of the arm 20 and at its outwardly projecting end receives the stud 19. The regulator mechanism is arranged to swing through an arc of approximately 90 degrees to lower the window into the well as indicated in broken lines in Figure 1.

It will be understood that the cross arm regulator as above described, except for the triangular plate 33, is adapted for use with a window glass, which moves straight up and down and is not formed with a slanting lower edge as illustrated on Figure 1. The result accomplished by use of the extension plate 33 could be achieved by replacing what might be termed the standard arm 20 with another arm provided with a bent end portion so designed that the stud or button 19 would be properly located with respect to the elongate slot or guide in the right hand retainer 18. However, to follow the latter procedure would add substantially to the cost of the regulator particularly when consideration is given to large scale production in which manufacture is carried on in connection with both the so-called standard cross arm regulator and a similar regulator for a window glass arrangement as above described. Thus by employing the simple and efficient expedient of the extension plate 33, the same regulator can be readily adapted for the window glass with a sloping lower edge.

It is to be understood that numerous changes in details of construction, arrangement and operation may be effected without departing from the spirit of the invention especially as defined in the appended claims.

What I claim is:

1. Window regulator mechanism comprising a pair of swinging relatively straight crossed arms pivotally connected together at the locality of their crossing to enable the arms to swing one past the other upon raising and lowering a window panel, the outer end portions of said arms from their point of pivotal connection being of approximately the same length; an extension plate secured to and projecting laterally from the outer panel, end of one arm, pivots on said extension plate and the end of said other arm, respectively, for connecting the same to the lower edge of a window panel, said pivots being of substantially the same radial distances from the point of pivotal connection of said crossed arms; a mounting for the opposite ends of said arms, and means for imparting operative swinging movement to said crossed arms.

2. Window regulator mechanism for actuating a window panel in substantially straight translatory movement, the lower edge portion of said window panel being substantially inclined between

its side edges, said mechanism comprising a pair of swinging arms pivotally connected together at the locality of their crossing to enable the arms to swing one past the other upon opening and closing movements of the window panel, the outer end portions of said arms from their point of pivotal connection being approximately straight and of approximately equal length, a triangular plate fixed to the outer end of one arm and having an apical portion projecting laterally therefrom, and pivots on said apical portion and on the end of said other arm, respectively, for connection to the inclined edge portion of the window panel, said pivots being of substantially the same radial distance from the point of pivotal connection of said swinging arms.

3. Window regulator mechanism for actuating a window panel in substantially straight translatory movement, the lower edge portion of said window panel being substantially inclined between its side edges, said mechanism comprising a pair of swinging arms pivotally connected together at the locality of their crossing to enable the arms to swing one past the other upon opening and closing movements of the window panel, the outer end portions of said arms from their point of pivotal connection being approximately straight and of approximately equal length, a separate adapter plate fixed to the outer end of one arm and having a portion projecting laterally therefrom, and pivots respectively connecting said laterally projecting portion and the end of the other arm to the inclined edge portion of the window panel, said pivots being of substantially the same radial distance from the point of pivotal connection of said swinging arms.
